UNITED STATES PATENT OFFICE.

JOHN DEVLIN, OF DETROIT, MICHIGAN.

DESIGN FOR A CLIP.

SPECIFICATION forming part of Design No. 24,663, dated September 10, 1895.

Application filed June 10, 1895. Serial No. 552,345. Term of patent 7 years.

To all whom it may concern:

Be it known that I, JOHN DEVLIN, a citizen of the United States, residing at Detroit, county of Wayne, State of Michigan, have 5 invented and produced a new and original Design for a Bonding Wire-Clip, of which the following is a full, clear, and exact description, reference being had to the accompanying drawings, which form a part of this specification.

My design consists of the clip hereinafter described and claimed, and illustrated in the drawings submitted herewith, in which—

Figure 1 is a view in perspective showing my 15 design. Fig. 2 is an end elevation of the same.

The leading feature of my design consists in a clip having a scalloped base and lateral elongated wings or sides.

A denotes the clip; a and a' , the sides, each 20 of circular outline at their base, the clip having, also, a central elongated raised rib A' between the sides, the scalloped or circular portions of the two sides meeting in said rib. The upper portions of the sides a a' project upward, as indicated at a^3 a^3 , above said rib.

What I claim is—

The design for a clip herein shown and described. 30

In testimony whereof I sign this specification in the presence of two witnesses.

JOHN DEVLIN.
